UNITED STATES PATENT OFFICE.

MASON H. CRITTENDEN AND FRANK V. EMERY, OF MINNEAPOLIS,
MINNESOTA.

FIREPROOF CONSTRUCTION.

SPECIFICATION forming part of Letters Patent No. 508,503, dated November 14, 1893.

Application filed April 3, 1893. Serial No. 468,832. (No model.)

To all whom it may concern:

Be it known that we, MASON H. CRITTENDEN and FRANK V. EMERY, citizens of the United States, residing at the city of Minneapolis, in the county of Hennepin and State of Minnesota, have jointly invented certain new and useful Improvements in Fireproof Construction for Plastering, of which the following is a specification.

10 Our invention relates to fire-proof construction for the interior of buildings adapted to sustain metallic lathing suitable for coating with plaster.

15 The principal object of the invention is to meet the common difficulty of providing a flat surface for ceilings in constructions where arched fire-proofing—either of metal, terra-cotta or other material—is used; and this we do by providing ceiling-joists formed of 20 flanged sheet-metal pieces fastened together and having their ends supported by the flanges of the floor-joists. This provides a level surface for the ceiling and enables metal lathing to be attached to the under sides of 25 the ceiling-joists by driving nails between their abutting parts.

Our improvements are illustrated in the accompanying drawings, in which—

Figure 1, shows a sectional elevation of a 30 floor and ceiling and their supports constructed in substantial accordance with our improvements; Fig. 2, an enlarged transverse section of the ceiling-joists and metallic lathing on the line $x-x$ of Fig. 1; Fig. 3, a side view, on the same scale as Fig. 2, of a portion of the ceiling-joist and metallic lathing; Fig. 4, a side view of one of the ends of a ceiling-joist; and Fig. 5, a transverse section of the same on the line $y-y$ of Fig. 4.

40 In such drawings 1 designates the floor; 2 the floor-joists of metal and I-shaped; and 3 a plate of corrugated sheet-metal in arched form with its ends supported at the junctures of the feet 4 and webs of the floor-joists. The 45 space 5 intervening the floor and the arched ceiling 3 may be wholly or partially filled with fire-proof material, or left vacant, as desired.

To enable metallic lathing to be attached 50 in horizontal position beneath the floor-joists, we provide the ceiling-joists 6 which are pref-

erably constructed of two strips of sheet-iron bent to channel-shape and secured together at proper intervals by rivets 7. The ends of the ceiling-joists thus constructed are made 55 to taper at a proper inclination, as indicated at 8, to conform substantially to the shape of the arched ceiling; and in the ends of the joists are provided slots 9 of proper shape to fit the feet or flanges of the floor-joists. The 60 metal at the upper edges of these slots is bent outward at opposite sides to form flanges 10 for the purpose of providing comparatively wide bases for seating the ceiling-joists on the feet of the floor-joists. Ceiling joists thus constructed and supported at suitable intervals, 65 are sufficiently strong and provide suitable means for attaching and supporting metallic lathing of almost usual construction.

In the drawings there is shown, for the purpose of illustrating the mode of attaching the lathing to the joists, a sheet-metal lathing 11 having at intervals grooves or depressions 12, and the lathing is shown to be attached by means of wire-nails 13 driven through the 75 lathing and between the sheets composing the ceiling-joists. As will be understood, there is sufficient elasticity in the sheet-metal members forming the joists to permit nails to be driven between them at intervals and force 80 the members slightly apart, while they serve to firmly clamp the nails. This spreading of the metal of the joists is indicated in Fig. 2, in somewhat exaggerated form, to plainly illustrate it.

85 The use of floor-joists and metallic lathing of the character and in the manner described is found, in practice, to overcome the difficulty usually experienced in providing a flat surface for plastering a ceiling where metal floor-joists and fire-proof arched ceilings are used in building construction.

It is not intended herein to claim broadly the character of ceiling-joists, or other building member described, for that feature is reserved to be claimed in another application, Serial No. 468,833, filed April 3, 1893, concurrently pending.

Having described our invention, what we claim is—

1. The combination with floor-joists, of ceiling-joists formed of channel-shaped sheet-

metal pieces secured together and having their ends supported by the feet of the floor-joists, and metallic lathing fastened to the ceiling-joists by nails driven between the 5 abutting parts of such ceiling-joists, substantially as set forth.

2. The combination with floor-joists having feet; of ceiling joists, supported by said feet, and composed of flanged sheet-metal parts 10 having plane surface backs secured together back to back and having sufficient elasticity to receive and hold nails driven in the joints between them; and metallic lathing attached by nails driven in such joints, substantially 15 as set forth.

3. The combination with floor-joists having feet; of ceiling-joists formed of flanged sheet-

metal parts having plane surface backs secured together back to back and having their ends slotted to receive the floor-joist feet; 20 and metallic lathing attached by nails driven in the joints between the parts of the ceiling-joists, substantially as set forth.

4. The combination with floor-joists having feet; of ceiling joists formed of flanged sheet- 25 metal parts secured together back to back and having their ends slotted to receive the floor-joist feet and having the upper edges of such slots flanged, for the purpose set forth.

MASON H. CRITTENDEN.
FRANK V. EMERY.
